UNITED STATES PATENT OFFICE.

GEO. C. HOWARD, OF PHILADELPHIA, PENNSYLVANIA.

MACHINE FOR PUNCHING AND PERFORATING.

Specification of Letters Patent No. 32,370, dated May 21, 1861.

To all whom it may concern:

Be it known that I, G. C. HOWARD, of Philadelphia, Pennsylvania, have invented certain new and useful Improvements in 5 Machinery for Perforating, Puncturing, or Cutting Sheets of Paper and other Material; and I do hereby declare the following to be a full, clear, and exact description of the same, reference being had to the accompanying drawing, and to the letters of reference marked thereon.

My invention relates to improvements in the machine for punching and perforating paper &c., for which an English patent, 15 No. 2607, was granted to W. and H. H. Bemrose, Deer. 11th, 1854, and my improvements consist, firstly, in a device for presenting the sheet of paper or other material, to the perforating, cutting, or punching 20 rollers; secondly, in a device for adjusting the sheet of paper or other material, to a proper position, prior to its passing between the said rollers; thirdly, in mechanism, which serves the double purpose of first 25 confining the sheet of paper before it is subjected to the perforating, cutting, or puncturing rollers, and then starting the machine; fourthly, in a mode of constructing the upper perforating roller, whereby 30 the pins or punches can be readily removed and replaced, and fifthly, in a peculiar manner of constructing the lower perforated roller.

In order to enable others to make and use 35 my invention, I will now proceed to describe its construction and operation.

On reference to the accompanying drawing which forms a part of this specification—Figure 1 is a front view of my improved perforating and cutting machine; Fig. 2 a transverse vertical section; Fig. 3 a plan view; Fig. 4 a vertical section of part of the machine drawn to an enlarged scale, and Figs. 5 and 6 detached sectional 45 views of portions of the perforating rollers, drawn to an enlarged scale, for the better illustration of my peculiar method of constructing the said rollers.

A and A' are the two side frames of the 50 machine, connected together at the bottom by the cross bars a and a', and above by the table B. In the opposite frames turns the main driving shaft C, the projecting end of which is furnished with a cog wheel 55 D, a fast pulley E, and a loose pulley F.

G is a bar fitting snugly, but so as to slide freely in a horizontal direction, only in openings in the opposite frames, one end of the bar being furnished with a strap guide b, and the opposite end being arranged to 60 operate a bell crank lever d, which is hung to a projection e on the frame A', and which will be more particularly alluded to hereafter.

In the opposite frames and above the shaft 65 C, turns a second shaft H, and above the latter a third shaft I, the former having a cog wheel K gearing into the wheel D, and having another cog wheel L gearing into a similar wheel M, on the upper shaft I, so 70 that on turning the driving shaft the two shafts H and I will revolve simultaneously in contrary directions to each other, but at the same speed.

The upper shaft I carries the upper perforating or cutting roller P, and the shaft H, the lower roller Q. The peculiar construction of these rollers will be especially alluded to hereafter, it will therefore suffice, for the present, to observe that the upper roller has 75 a series of pins or punches y corresponding as regards number and position to the teeth on the wheel M, and that the lower roller has a number of holes corresponding with and arranged to receive the pins of the upper 80 roller so that paper or other material passed between the rollers as the latter revolve will receive a row of perforations.

At the rear of the shaft H and turning in 85 projections f of the opposite frame is a 90 roller N which is driven in the direction of the arrow at an appropriate speed by any suitable system of gearing connected with the shaft H and around this roller passes an endless band i which also passes around 95 another roller R, the latter being allowed to turn freely in suitable staples on the underside, and near the rear edge of the table B, both rollers being so situated in respect to the upper surface of this table, that the endless band can traverse freely in contact with the said upper surface. Directly above the roller N is another roller s, the journals of 100 which are allowed to turn freely in the ends of the arms T, T, which are secured to a spindle t, the ends of the latter being hung loosely to the opposite frames A and A' of the machine. To one of these arms T is jointed a rod h, which passes through an eye in the horizontal arm of the bell crank 105 110

lever *d*, the latter being connected by means of another rod *h*, to the outer end of a treadle *l*, which is hung to a cross bar connected to the lower ends of the opposite frames *A* 5 and *A'*.

It will be observed that the lower end of the rod *h*, has a projection or enlargement *j* which rests on the horizontal arm of the bell crank lever *d*, and serves to maintain the 10 said rod, the arms *T*, *T*, and the roller *S*, in the elevated position shown in Fig. 4 as long as the said horizontal arm of the bell crank is not depressed by means of the treadle. When this depression takes place, 15 however, the rod will descend, causing the roller *S* to fall, either by its own weight, or by the assistance of springs, onto the endless band *i* above the roller *N*, and assume the position shown in red lines. On releasing 20 the treadle however the recoil of a spiral spring *n*, will cause the bell crank lever, as well as the roller *S*, to assume its former position.

The vertical arm of the bell crank lever *d*, 25 bears, when the treadle is released, against a pin or projection on the bar *G*, and thus holds the latter in such a position that the driving strap will be retained by the guide *b* on the loose pulley *F*, but when the treadle 30 is depressed the bell crank lever bearing against another pin on the bar will move the latter, so that the guide will transfer the driving strap from the loose to the fast pulley. The two pins of the bar however are 35 at such a distance apart from each other, that the arm of the bell crank lever has a limited play between them for a purpose which will be rendered apparent hereafter.

It will be observed that a fine line *w* is 40 stretched from the spindle *t*, to the back of the table, and that this line coincides with the pins of the upper perforating roller, and the holes of the lower roller, and is situated at right angles to the center line of rotation 45 of the shafts *H* and *I*.

Supposing a sheet of postage stamps has to receive a row of perforations between each row of stamps, the operator, who is seated at the rear of the table, takes the sheet, places 50 it beneath the line *w*, on the endless band *i* and pushes it forward until its outer edge is immediately beneath the roller *S*, taking care that the space between the stamps coincides with the line *w* which thus serves as 55 a register. Having thus adjusted the sheet, the operator depresses the treadle to a limited distance, thereby allowing the roller *S* to fall and bear on the end of the sheet, which is now in a proper position to be 60 submitted to the perforating rollers. The operator now continues the depression of the treadle thereby moving the bar *G* (which during the first movement of the bell crank lever had remained stationary owing to the

play of its vertical arm between the pins of 65 the bar) and transferring the driving strap from the loose to the fast pulley, thereby causing the upper and lower perforating rollers, as well as the roller *N*, to revolve in the direction of their arrows. The sheet by 70 the combined movement of the endless band and roller *S* is pushed forward and between the perforating rollers through the action of which it receives a row of holes in the exact line desired, owing to the preliminary adjustment of the sheet in respect to the line *w*. As the sheet is subjected to the rollers, it passes beneath a slotted tongue *x*, Fig. 4, which is secured to the spindle *t*, and which serves to strip the sheet from the perforating 75 pins of the roller *P*. The moment the sheet has received the desired row of perforations the treadle is released, the roller *S* rises and the moving parts of the machine become stationary, preparatory to a repetition of the 80 85 above described operations.

It will be observed that each of the shafts *H* and *I* is provided with a key or feather so that the perforating rollers can be adjusted to any desired position longitudinally on 90 their respective shafts, to which, if necessary, additional rollers may be applied.

The peculiar construction of the perforating rollers will be best observed on reference to Figs. 5 and 6. One face of the upper 95 roller *P* has an annular recess for the reception of a detachable annular plate *p*, the edge of which fits snugly against the inside of the flange *q*, a number of holes being bored in this flange for the reception of pins *y*, which 100 have conical heads adapted to the countersunk holes.

It will be readily seen that on removing the annular plate *p*, any one or more of the pins may be withdrawn and replaced at 105 pleasure. The importance of this arrangement will be understood when it is borne in mind that on account of the rapidity with which the perforating rollers revolve, the pins are liable to wear and frequently require to be replaced with new ones.

It is important that the periphery or flange of the under roller *Q*, should be as thin as possible at the point where the holes for the reception of the pins of the upper roller are 115 situated, so that the pieces punched from the paper or other material to be perforated, may have no tendency to stick fast in the holes and choke the same, a ready discharge of the punched pieces being advisable in 120 order to allow for the free movement of the punches in and out of the holes.

In order to obtain this desired thinness of flange, and at the same time to impart to it proper strength, I construct the lower 125 roller *Q*, in the manner shown in Figs. 5 and 6, on referring to which it will be seen that, although the flange, through which the pins

pass, is appropriately thin the necessary strength is imparted to it by an internal flange p .

Although I have described the machine as used for perforating, it will be evident that by altering the shape of the pins y , it may be applied to the puncturing only, or to the cutting of longitudinal slits in paper or other material or otherwise wholly or partially severing the same.

I wish it to be understood, that I do not desire to claim broadly, revolving rollers for punching and perforating sheets of paper and other material, inasmuch as such rollers are illustrated and described in the English patent No. 2607, granted to W. and W. H. Bemrose, December 11th 1854. But

I claim as my invention, and desire to secure by Letters Patent—

1. The endless band i , the table B , and vibrating roller S , arranged in respect to the perforating, cutting, or puncturing rollers P , and Q , substantially as set forth, for the purpose of presenting a sheet of paper or other material, to the said rollers.

2. In combination with the said perforating, cutting, or puncturing rollers, the line w , arranged above the table B , substantially as set forth, for the purpose of adjusting the

sheet of paper or other material, to a proper position, prior to being subjected to the action of the rollers.

3. The treadle l , or its equivalent, in combination with the strap guide b , and vibrating roller S , and the devices herein described or their equivalents, whereby the depression of the said treadle allows the roller S to fall in the first instance, the further depression operating the strap guide as set forth for the purpose specified.

4. Constructing the roller P with a recess in the face for the reception of the annular plate p , and with a flange q , having countersunk holes for the reception of the pins or punches y , as and for the purpose herein set forth.

5. The under roller Q having a thin periphery with holes, for the reception of the punches of the upper roller, and an internal strengthening flange v , as described.

In testimony whereof, I have signed my name to this specification, in the presence of two subscribing witnesses.

GEO. C. HOWARD.
